UNITED STATES PATENT OFFICE.

GEORGE K. CUMMINGS, OF NEW YORK, N. Y.

DESIGN FOR A PRISM-WINDOW.

SPECIFICATION forming part of Design No. 33,671, dated December 4, 1900.

Application filed August 15, 1898. Serial No. 688,628. Term of patent 7 years.

To all whom it may concern:

Be it known that I, GEORGE K. CUMMINGS, a citizen of the United States, residing at New York, in the county and State of New York, have invented and produced a new and original Design for Prism-Windows, of which the following is a specification.

My invention relates to a new and original design for prism-windows, and is illustrated in the accompanying drawings, in which—

Figure 1 is an elevation or front view of a prism-window embodying my said design, and Fig. 2 is a vertical cross-section through the middle of the window.

As shown in the accompanying drawings, my design consists of panes, plates, or lights of parallel prisms represented by the light parallel lines and inclosed within a rectangular parallelogram and separated by a framework represented by double lines and arranged as follows: Within a rectangular parallelogram are a number of rectangular, square, or approximately square prism-lights arranged in vertical and horizontal rows, each

two adjacent vertical rows separated by a single row of hexagonal prism-lights elongated vertically and each two adjacent horizontal rows separated by a single row of hexagonal prism-lights elongated horizontally. The parallel prisms extend from side to side of each of the lights above described and from side to side of the window or entire design.

The portion of the design connecting the four-sided and hexagonal lights and which represents the framework, as above stated, consists of double lines.

The whole design gives the appearance of a barred or grated prism or lined window.

I claim—

The design for a prism-window as herein shown and described.

In testimony whereof I have signed my name to this specification in the presence of two subscribing witnesses.

GEORGE K. CUMMINGS.
